UNITED STATES PATENT OFFICE.

JAMES HENRY McCUTCHEON, OF COLLINGWOOD, ONTARIO, CANADA.

RUDDER CONSTRUCTION.

Application filed February 12, 1924. Serial No. 692,379.

To all whom it may concern:

Be it known that I, JAMES HENRY McCUTCHEON, a subject of the King of Great Britain, and a resident of the town of Collingwood, in the county of Simcoe, in the Province of Ontario, Canada, have invented certain new and useful Improvements in Rudder Constructions, of which the following is the specification.

10 My invention relates to improvements in rudder constructions and the object of the invention is to devise a simple means whereby the tail shaft may be unshipped without unshipping the rudder.

15 A further object is to provide means for swinging the rudder rearwardly about a knuckle or joint in the rudder stock for permitting the removal of the propeller wheel and tail shaft complete without the necessity of detaching the former from the latter, and it consists essentially of a rudder post carrying a rudder blade, and having an orifice formed therein so positioned that when the rudder blade is turned at right angles to the propeller shaft, such orifice is in central alignment with the propeller shaft, so that such shaft may be drawn outward through the orifice for repair or replacement, as hereafter more particularly

30 explained by the following specification.

Fig. 1 is a side elevation of my rudder showing it mounted upon the stern post of a ship.

35 Fig. 2 is a sectional plan view of the part shown in Figure 1.

Fig. 3 is an elevational detail partly in section showing my rudder stock and the construction of the knuckle or joint thereon. The dotted lines show the lower portion of 40 the stock to which the rudder is attached swung rearwardly for the purpose above described.

In the drawings like characters of reference indicate corresponding parts in each 45 figure.

1 indicates the stern post of a ship, provided with the usual stern tube 2, containing the stern bearing 3 in which is mounted the tail shaft 4 carrying the propeller 5.

50 6 is a shoe formed at the bottom of the stern post 1, in the forward end of which is located the step-bearing 7.

55 8 is the rudder stock which is journaled in the vicinity of its upper end in a collar bracket 9 carried by the stern post 1, and at its lower end stepped into the bearing 7.

The rudder stock 8 is provided intermediate of its length with an off-set 8^x.

10 is the rudder of the balanced type suitably secured to the rudder stock 8, by straps 60 12, 13, 14 and 15, the rudder comprising the main portion 10 and the counter balance 11.

16 is an orifice which is formed partially in the counter balance 11 and partially in the main portion 10 of the rudder, the conformation of the offset 8^x of the rudder stock being such that it will lie clear of the orifice 16.

17 is a filler plate fitting within the orifice 16 and secured in position by a vertical strap 70 18, which is secured at 19 and 20 to the counter balance 11.

The rudder stock 8 is divided into upper and lower portions, the lower portion being secured to the rudder as above described, the 75 joint being situated immediately above the rudder and below the collar bracket 9. 21 is a circular enlargement at the bottom of the upper portion of the stock, normally secured to the circular enlargement 22 at the 80 top of the lower portion of the stock by means of the bolts 23; the rear faces of such enlargements 21 and 22 are also hinged together by the hinge 24 for a purpose which will hereinafter appear. 85

When it is desired to withdraw the tail shaft for renewal or repair, all that it is necessary to do is to remove the strap 18 and the filler plate 17, then swing the rudder hard over into a position at right angles to 90 the tail shaft or to the position shown by dotted lines in Figure 2. When this is done, the orifice is in alignment with the tail shaft 4, and is sufficiently large to permit of the free withdrawal of the tail shaft 95 therethrough, with sufficient clearance. The tail shaft may be replaced in the same manner and the filler plate 17 again applied to the counter balance portion of the rudder.

When it is desired to remove the tail 100 shaft and propeller wheel without detaching the latter, it is only necessary to jack up the rudder until its foot is unshipped from the bearing 7, and then if the bolts 23 have been removed, to swing back the 105 rudder about the hinge 24 until it is clear of the wheel, when the wheel and tail shaft can be readily removed together.

From this description it will be seen that I have devised a very simple means whereby 110 a tail shaft may be easily removed from the ship without unshipping the rudder, and in

addition have provided means whereby the rudder can be swung rearwardly about its jointed stock to facilitate the removal of the propeller wheel and tail shaft complete, 5 without the necessity of completely unshipping the rudder.

What I claim as my invention is:

1. In a ship, the combination with the stern post and tail shaft, of a rudder turn- 10 ably mounted upon the stern post and pro- vided with an orifice adapted to be brought into alignment with the tail shaft when the rudder is turned at right angles to such shaft to permit the withdrawal of the shaft 15 through the orifice.
2. In a ship, the combination with the stern post and tail shaft, of a rudder stock, a rudder comprising a main portion and a counterbalance, an offset portion formed in 20 the stock, said rudder having an orifice po- sitioned partly in the main portion and partly in the counterbalance through which the tail shaft may be drawn when the rudder 25 is set at right angles thereto.
3. In a ship, the combination with the stern post and tail shaft, of a rudder stock, a rudder comprising a main portion and a counterbalance carried by the stock and having an orifice formed therein through 30 which the tail shaft is adapted to be drawn when the rudder is set at right angles to the propeller shaft, a filler plate for such orifice, and means for securing the filler plate in position.
4. In a ship, the combination with the rudder stock, of a rudder mounted thereon, said stock being jointed immediately above the rudder, detachable means for securing the jointed portions of the stock in their 40 aligned position, means for hinging the por- tions of the rudder stock together for per- mitting the rudder to be swung rearwardly

upon the removal of the detachable securing means.

5. In a ship, the combination with a rudder- 45 stock jointed intermediately of its length, a rudder mounted on the lower por- tion of the stock, coacting enlargements at the upper end of the lower portion of the stock and at the lower end of the upper por- 50 tion of the stock, said enlargements be- ing hinged together at their back and de- tachable means for securing the respective enlargements together.

6. In a ship, the combination with a rudder- 55 stock, of a rudder mounted thereon, said stock being jointed immediately above the rudder, detachable means for securing the jointed portions of the stock in their aligned position, means for hinging the portions of 60 the rudder stock together for permitting the rudder to be swung rearwardly upon re- moval of the detachable securing means, said rudder having a tail shaft receiving orifice extending therethrough, and an off- 65 set on the lower portion of the stock adapted to clear the orifice in the rudder.

7. In a ship, the combination with a rudder- 70 stock, of a rudder mounted thereon, said stock being jointed immediately above the rudder, detachable means for securing the jointed portions of the stock in their aligned position, means for hinging the por- 75 tions of the rudder stock together for per- mitting the rudder to be swung rearwardly upon removal of the detachable securing means, said rudder having a tail shaft re- ceiving orifice extending therethrough, an offset on the lower portion of the stock adapted to clear the orifice in the rudder, and a detachable filler plate normally clos- 80 ing the orifice in the rudder.

JAMES HENRY McCUTCHEON.
